AUTOMATIC TELEPHONE SYSTEM

Application filed August 27, 1927, Serial No. 215,859, and in Germany September 15, 1926.

This invention relates to telephone systems in general and particularly to automatic telephone systems, in which calls of different value are set up over the same connecting devices and lines, and in which a call according to its value is steered by switching devices, which are caused to function in different ways according to the number of initial impulses received before the positioning impulses are received.

10 The steering of the connecting devices by the initial impulses takes up a certain amount of time, and it may happen that the first positioning impulse is transmitted before this steering has been completed, and this may cause traffic disturbances of wrong connections.

15 The object of this invention is to remove these difficulties, this being achieved in a simple manner in that an impulse repeater located at the outgoing end of the junction line is provided with a relay device, which is under the control of positioning impulses and causes the impulse receiving relay to function only after one or more impulses have been received and after the train of impulses have ended it causes the repeater relay to transmit a corresponding number of additional impulses.

20 The figures show by way of example a circuit for setting up local and trunk calls over a two-wire junction line and the same final selector.

25 The Fig. 1 shows a subscriber's station N1, which can be connected over a preselector VW to the group selector, GW, to the bank contacts of which is connected over a repeater Ue 1 the outgoing end of two-wire junction lines. This repeater Ue 1 can also be reached over a preselector FVW for setting up trunk calls. The preselector FVW is connected to a jack FK1 located at the trunk position FP1. The incoming end of the two-wire junction line terminates at a repeater 30 Ue 2, which is shown in Figure 2 and has associated with it a final selector LW, Fig. 3, for local and trunk calls.

35 The general method of operating this arrangement will now be described.

40 When a subscriber takes into use the re-

peater Ue 1 at the outgoing end of a two-wire junction line VL, an initial impulse is transmitted over the junction line VL; thereby the switching devices embraced in the repeater Ue 2 are so affected that they steer 55 the final selector when a local connection is set up. When, however, the trunk position FP1 has been connected to the repeater Ue 1, then two initial impulses are transmitted over the junction line VL before the positioning impulses, and the devices at the repeater Ue 2 at the incoming end of the junction line VL are caused to steer the final selector for setting up a trunk connection.

45 A description will now be given of the method of operating the circuits shown in the accompanying drawings when a local call and a trunk call are set up. For this purpose it will be assumed that the subscriber's station N 1 indicated in Fig. 1 wishes to set 50 up a connection with a subscriber, who can be reached over the final selector LW shown in Figure 3. When the receiver is taken down, the connecting devices, which precede the repeater Ue 1, are taken into use in 55 known manner and the group selector is raised to the desired level by dialling the first digit. The group selector then hunts for an idle repeater. Assuming that the repeater Ue 1 is the first free one in that level, 60 the following circuit is established: earth at the group selector GW, back contacts 9 f, 34 c 1, 11 h, 21 n, winding of relay X, battery, earth. The relay X is energized and switches over its contacts. At the contacts 22 x and 23 x the source of alternating current WQ is applied to the left hand windings of the repeater 24 in the junction line VL, thereby 65 energizing over the leads La and Lb the alternating current relay J 2 in Figure 2 at the 70 incoming end of the junction line. At contact 5 x the relay Cl (winding I) is energized, at 35 Cl it closes a locking circuit for its 75 second winding, at the change-over contact 36 c 1 the upper speaking lead is switched through to the winding of the impulse receiving relay A 1 and at 34 c 1 is opened the 80 circuit of the relay X, which now disconnects the source of alternating current from 85 the junction line at the contacts 22 x and 23 x. 100

Thus only a short impulse is transmitted over the junction line VL to the repeater Ue 2. The relay E is energized over the contacts 38 c 1 and 6 x, and it locks itself over its contact 3 e. The relay E switches over its contacts and energizes the relay N over: earth, contact 2 e, back contact 10 f, winding of relay N, battery, earth.

If the subscriber now dials the second digit, 10 the relay A 1 is energized by the first current impulse over: earth at the preceding connecting device, a-lead, front contact 36 c 1, back contacts 32 i 1, 33 p 1, winding of relay A 1, battery, earth. The relay A 1 switches 15 over its contact 13 a 1, thereby closing the following circuit for the relay U; earth, front contact 13 a 1, back contact 18 m, winding I of relay U, resistance W 1, battery, earth. The relay U actuates its contact 16 u and 20 after relay A falls back the relay M is energized in the following circuit: earth, front contact 16 u, winding I of relay M, winding I of relay U, resistance W 1, battery, earth. The winding I of relay U is short circuited 25 at contact 18 m and at the same time the short circuit is removed from the winding II of relay U, so that the relay U remains energized over its second winding and the contact 13 a 1 as relay A 1 responds to the 30 impulses. The relays U and M maintain themselves energized during the impulse transmission. The relays are so connected that the contact 12 a 1 has already fallen back when the contact 22 m is actuated. The 35 relay M switches over its contact 22 m, hence during the subsequent number impulses the relay X is operated each time the relay A is energized. The relay X is energized over: earth, impulse contact 12 a 1, front contacts 40 22 m, 21 n, winding of relay X, battery, earth. The contacts 22 x and 23 x repeat the impulses to the repeater Ue 2. After the last impulse when the contact 13 a 1 has fallen back, the relay U is first deenergized. Relay 45 M is a slow acting relay and falls back later, thus the relay X is again energized over: earth, back contact 23 u, front contacts 22 m, 21 n, winding of relay X, battery, earth. The repeated impulses operate repeater Ue 2 and final selector LW in known manner.

In order to release the connecting devices it is necessary to transmit a comparatively long alternating current impulse from the source of alternating current WQ at the repeater Ue 1 to the alternating current relay J 2 at the repeater Ue 2.

The circuit of the relay C 1 at the repeater Ue 1 was interrupted at the group selector. The relay C 1 falls back and at its contact 55 37 c 1 it closes a circuit for energizing the relay M (winding II), which actuates its contact 22 m and thereby establishes a circuit for the relay X: earth, back contact 23 u, front contacts 22 m and 21 n, winding of relay X, battery, earth. Relay X at its con-

tacts 22 x and 23 x connects the source of alternating current WQ to the junction line VL, and after a comparatively long time the circuit of relay X is opened at contact 21 n, because the relay N has locked itself over earth, front contacts 5 x and 1 e. The circuit of relay X is not interrupted until relay E, which is slow to release, has opened this locking circuit at contact 1 e and the relay N has fallen back after a little delay.

A description will now be given of the setting up of a trunk call over the junction line VL to a subscriber connected to the final selector LW in Fig. 3. The wanted subscriber's number is given to the operator at the trunk position FPl in any desired manner. The operator throws the dialling switch and inserts the plug St into an idle jack FKz. The preselector FVW connected to this jack hunts for an idle repeater Ue 1 connected to a junction line outgoing in the required direction. The throwing of the dialling switch connects battery at contact n 1 over the contact springs 102, 103 and 104, lead 110, plug St, jack FKz, upper wiper of FVW and over contact 36 c 1 to the winding I of relay F. Relay F operates and at contact 9 f removes the short circuit from its winding II, so that this is energized in series with relay X over the cut-off relay of FVW. Relay X at its contacts 22 x and 23 x applies the source of alternating current WQ to the left hand windings of repeater 24 of the junction line VL, thereby energizing over the leads La and Lb the alternating current relay J 2 in Fig. 2 at 100 the incoming end of the junction line. Relay C 1 is energized over contact 5 x, and over contact 35 c 1 it closes a locking circuit for its second winding and the winding II of relay F. At the change-over contact 36 c 1 it switches the upper speaking lead through to the winding of the impulse receiving relay A 1 and at contact 34 c 1 it opens the circuit of relay X, which at contacts 22 x and 23 x now disconnects the source of alternating current from the junction line (first initial impulse). Relay E is energized over earth, front contact 38 c 1, back contact 6 x, winding of relay E, battery, earth. At contact 3 e the relay locks itself, and it also switches over the contacts 1 e and 2 e: over the latter the relay X is energized a second time over: earth, front contacts 2 e, 10 f, back contact 21 n, winding of relay X, battery, earth. Over earth, front contacts 5 x, 1 e, winding of relay N, battery, earth, the relay N is energized and at contact 21 n it opens the circuit of relay X. Thereby a second initial impulse is sent by the contacts 22 x and 23 x from the alternating current source WQ over the junction line to the alternating current relay J 2 at the incoming end of the junction line. Relay N locks itself at contact 13 n over: earth, front contacts 38 c 1, 13 n, winding of relay N, battery, earth. When the trunk operator then dials, the same 105 110 115 120 125 130 135 140 145 150 155 160 165 170 175 180 185 190 195 200 205 210 215 220 225 230 235 240 245 250 255 260 265 270 275 280 285 290 295 9840 9845 9850 9855 9860 9865 9870 9875 9880 9885 9890 9895 990

operations take place as above described for a local call. The further setting up of the connection as far as initiating the testing is completed in known manner.

5 To initiate the testing, the operator throws the test key PS. Thereby battery is applied over the key PS, contact springs 141 and 104 of the key PS, leads 110, 111, jack spring 112, upper wiper of FVW, contacts 36 c 1, 32 i 1, 10 135 p 1, to the winding of relay G, the other end of which is connected to earth over the contacts 14 m, 10 f and 2 e. Relay G is operated in this circuit and at contact 7 g closes the operating circuit of the relay M (winding 15 II). Relay X is now operated over: earth, back contact 23 u, front contacts 22 m and 21 n, winding of relay X, battery, earth. At contacts 22 x and 23 x the alternating current source WQ is connected to the junction line 20 VL. But relay M at the same time at contacts 14 m opens the circuit of relay G, which at contact 7 g opens the circuit of relay M. The latter falls back slowly and at its contact 22 m it releases the relay X. The alternating current source WQ is again connected up at the contacts 22 x and 23 x. Hence a short impulse is sent over the junction line to 25 initiate the testing. Other testing operations and the release of the connection takes place 30 in known manner.

What is claimed is:

1. In a telephone system, a trunk line, means for establishing a connection to said trunk line, means responsive to the establishment of the connection for transmitting a preliminary impulse over said trunk line, means for transmitting a group of digit impulses over the established connection, and means for preventing the digit impulses from 35 being effective prior to the transmission of the preliminary impulse.

2. In a telephone system, a trunk line, means for establishing a connection to said trunk line, means responsive to the establishment of the connection for transmitting a preliminary impulse over said trunk line, means for transmitting a group of digit impulses over the established connection, and means for preventing the digit impulses from 40 being effective prior to the transmission of the preliminary impulse, said last named means including means for rendering the first digit impulse ineffective and for producing an additional impulse after the last digit impulse 45 has been transmitted.

3. In a telephone system, an impulse repeater including an impulse receiving relay and an impulse repeating relay, means for transmitting a group of digit impulses to the receiving relay, and means responsive to the first impulse transmitted for preparing said repeating relay to repeat the subsequent impulses and to transmit an additional impulse responsive to the cessation of the impulses 50 transmitted to the receiving relay.

4. In a telephone system, an impulse repeater including an impulse repeating relay and a relay device, means for transmitting a group of digit impulses to the repeater, and means responsive to the first impulse received for rendering said impulse relay controllable by subsequent impulses and for conditioning the relay device so that the impulse repeating relay shall repeat the subsequent digit impulses and then an impulse corresponding to the first impulse received. 70

5. In a telephone system, an impulse repeater including an impulse repeating relay and a relay device, means for transmitting a group of digit impulses to the repeater, means responsive to the first impulse received for conditioning the relay device so that the impulse repeating relay shall repeat the subsequent digit impulses, and means for operating the impulse repeating relay responsive to the restoration of the relay device to transmit an impulse corresponding to the first impulse received. 80

6. In a telephone system, an impulse repeater including an impulse repeating relay and a relay device, means for transmitting a group of digit impulses to the repeater, means for operating the relay device during the transmission of the digit impulses, means controlled by the relay device for causing the impulse repeating relay to repeat the impulses subsequent to the first impulse, and means for again operating the impulse repeating relay responsive to the restoration of the relay device upon the cessation of the transmission of digit impulses to transmit another impulse. 90

7. In a telephone system, a device for repeating a group of impulses, means in said device for always adding an additional impulse to the group repeated, and an outgoing loop circuit over which both the repeated impulses and the additional impulse are transmitted. 105

8. In a telephone system, a selector having a trunk line extending thereto, means for selecting said trunk line, the selection of said trunk causing an impulse to be automatically transmitted to said selector to prepare it to operate in a certain manner, and means for transmitting additional predetermined impulses over said trunk to cause the operation of said selector. 110

9. In a telephone system, means for transmitting a predetermined number of impulses, means for receiving said impulses, and means for automatically transmitting an impulse in advance of said predetermined impulses for preparing said receiving means to respond to said predetermined impulses. 120

10. In a telephone system, means for transmitting a predetermined number of impulses, means for receiving said impulses, and means for automatically transmitting one or more impulses in advance of said predetermined 125

impulses to prepare said receiving means to function in response to said predetermined impulses, the manner in which said receiving means functions depending upon the number of automatically-transmitted impulses.

11. In a telephone system, a trunk comprising a plurality of conductors, a device for repeating a series of digit impulses over a circuit comprising two conductors of said trunk in series, and means in the device whereby an additional impulse is transmitted over the same circuit immediately following the last impulse of the repeated series of impulses.

12. In an impulse repeater for receiving and retransmitting a series of evenly spaced digit impulses, means responsive to the seizure of the repeater for transmitting a preliminary impulse, and means responsive to the receipt of the first impulse, of a series for rendering the repeater effective to retransmit the subsequent impulses of the series.

13. In an impulse repeater for receiving a series of digit impulses over any one of a plurality of paths and for retransmitting a similar series of impulses, means responsive to the seizure of the repeater over one path for transmitting one preliminary impulse, means responsive to the seizure of the repeater over another path for transmitting a plurality of preliminary impulses, and means responsive to the receipt of the first impulse of the series for rendering the repeater effective to retransmit the subsequent impulses of the series.

14. In an impulse repeater, an impulse receiving relay, an impulse repeating relay, and means responsive to the receipt of the first impulse of a series for rendering said repeating relay effective to repeat subsequent impulses of the series coincidentally with their receipt by the receiving relay.

15. In an impulse repeater, a relay adapted to respond to each impulse of a series, a second relay controlled by said first relay for repeating said impulses except the first of the series, and means for causing said second relay to transmit an additional impulse following the last impulse repeated.

16. In a telephone system, a trunk line comprising two sections, a relay adapted to respond to impulses transmitted over the first section of the trunk line, a second relay controlled by said first relay for transmitting corresponding impulses over the second section of the trunk line, and means for delaying the effective action of the second relay for a period of time equal to the duration of a complete impulse cycle.

17. In a telephone system, a trunk line comprising two sections, a relay adapted to respond to each impulse of a series received over the first section of the trunk line, a second relay controlled by said first relay for transmitting a similar series of impulses over the second section of the trunk line, and means for displacing the transmitted series

with respect to the received series so that the first transmitted impulse corresponds to the second received impulse.

18. In a repeater terminating a two conductor trunk line, means for receiving a group of digit impulses, and means for cancelling the first impulse of the group and for retransmitting subsequent impulses of the group over the two conductors of the trunk line in series coincident with the receipt of such impulses.

19. In an impulse repeater terminating a two conductor trunk line, means for receiving a group of digit impulses and for transmitting a similar group of impulses over the two conductors of the trunk line in series, and means for delaying the retransmission of impulses until and dependent upon the receipt of the second impulse of the group.

20. In an impulse repeater terminating a two conductor trunk line, means for receiving a group of digit impulses and for transmitting a similar group of impulses over the two conductors of the trunk line in series, and means for displacing the transmitted group of impulses with respect to the received group so that the first transmitted impulse corresponds to the second received impulse.

21. In a repeater terminating a trunk line comprising two talking conductors, means for receiving a group of digit impulses, means for cancelling the first impulse of the group and for repeating subsequent impulses of the group over the two talking conductors of the trunk line in series, and means for transmitting an additional impulse over the trunk line following the last impulse repeated.

22. In a telephone system, an incoming trunk line and an outgoing trunk line each comprising two talking conductors, an impulse repeater connecting said trunk lines, means for transmitting a group of digit impulses over one conductor of the incoming trunk line, and means in the repeater for cancelling the first impulse of said group and for repeating subsequent impulses of the group over the two conductors of the outgoing trunk line in series.

23. In a telephone system, an incoming trunk line and an outgoing trunk line each comprising two talking conductors, an impulse repeater connecting said trunk lines, means for transmitting a group of digit impulses over one conductor of the incoming trunk line, means in the repeater for cancelling the first impulse of said group and for repeating subsequent impulses of the group over the two conductors of the outgoing trunk line in series, and means in the repeater for transmitting an additional impulse over the outgoing trunk line following the last repeated impulse.

24. In a repeater adapted to respond to a series of direct current impulses, means for transmitting a corresponding series of alter-

nating current impulses, and means for delaying the transmission of impulses until and dependent upon the receipt of the second direct current impulse.

5 25. In a repeater adapted to respond to a series of direct current impulses, means for transmitting a series of alternating current impulses, and means responsive to the first direct current impulse of the series for adapting said first means to be controlled by subsequent direct current impulses of the series.

10 In witness whereof, I hereunto subscribe my name this 1st day of August, A. D. 1927.

MAXIMILIAN MATHIAS.
